APPARATUS FOR PRESSING GARMENTS

Thomas Crocella, New York, N. Y.

Application February 21, 1936, Serial No. 65,082

3 Claims. (Cl. 38—42)

This invention relates to apparatus for pressing garments and has particular reference to an improved apparatus which facilitates the lifting and moving of the iron during the pressing operation, while permitting of the free and unhampered movement thereof.

The invention broadly comprehends a pressing apparatus which is so constructed and arranged as to exert a tensioned lift or resilient upward pull on the pressing iron to thereby lessen the effort required to lift and move the same and which permits of the free longitudinal and lateral movement of the iron over the pressing board.

15 The invention more specifically includes an elevated supporting track, a pressing iron suspension means including a trolley associated with and guided by the track together with a contractile spring depending from the trolley and connected with the pressing iron for exerting a resilient upward pull on the pressing iron to serve as an auxiliary or a supplemental means for facilitating the lifting and moving of said pressing iron and thereby relieve the operator of a portion of the labor incident to the pressing of garments.

20 With the foregoing and other objects in view, reference is now made to the following specification and accompanying drawing in which there is illustrated a preferred embodiment of the invention, while the appended claims cover variations and modifications thereof which fall within the scope of the invention.

In the drawing:

25 Fig. 1 is a perspective view illustrating an apparatus embodying the invention.

Fig. 2 is an enlarged view of the trolley.

30 Referring to the drawing by characters of reference, the apparatus includes a supporting structure or table 10 upon the upper surface of which is mounted a garment pressing board 11 and an insulated pressing iron rest 12 on which the pressing iron 13 is placed when not in use.

In order to provide means for facilitating the 35 lifting and moving of the pressing iron during the pressing operation, the table 10 is provided with a pair of oppositely disposed standards 14 extending upwardly from the top thereof and to the upper end of which is secured a supporting track 15 extending longitudinally of the pressing board 11 and in superposed relation thereto. A pressing iron suspension means, indicated generally by the reference character 16, includes a sheave or trolley 17 associated with the track 15 for longitudinal guided rolling movement there-

over and which sheave or trolley is journaled in a depending bearing block 18 to which is connected a depending contractile spring 19 attached at its lower end to the handle of the pressing iron 13.

By this construction, the sheave or trolley 17 is capable of longitudinal rocking movement on the track 15 and laterally with respect thereto so that the suspension means 16 has a universal swinging movement with respect to the track 15 whereby free and unhampered longitudinal and lateral movement of the pressing iron 13 is permitted while the spring 19 serves as an auxiliary or supplemental means for facilitating the lifting of the pressing iron 13 from the iron rest 12 to the garment pressing board 11 and vice versa in addition to relieving the operator of a portion of the labor incident to the pressing of the garment.

The track 15 is preferably a wire or rod of circular shape in cross sectional configuration which is stretched between the standards 14, the standards being connected at their upper ends by a cross bar 20 for preventing inward flexing of the standards. The bearing block 18 is provided in one side face thereof with an opening 21 through which the track 15 passes when the block is applied thereto or removed therefrom.

For the purpose of preventing injury to the operator in the event of accidental disengagement of the bearing block from the track, a cable 22 is attached at its opposite ends respectively to the upper end of the block and to the cross bar 20, the cable being of a sufficient length to permit of the movement of the trolley on the track.

What is claimed is:

1. In an apparatus of the character described, an elevated supporting track, a pressing iron and a suspension means including a trolley associated with and longitudinally guided by the track, and a laterally flexible contractile spring depending from the trolley and means connecting the lower end of the spring with the forward end of the handle of the pressing iron for exerting a resilient upward pull on the pressing iron and an upward tilting thereof when in operation for facilitating the lifting and moving of the same.

2. In an apparatus of the character described, an elevated supporting track, a pressing iron and a suspension means associated with said track for longitudinal guided movement and including a trolley rollable along said track, and a laterally flexible contractile spring depending from the trolley and means connecting the lower end of

the spring with the forward portion of the pressing iron for exerting a resilient upward pull on the pressing iron and an upward tilting thereof when in operation for facilitating the lifting and moving of the same.

3. In an apparatus of the character described, a table, a pressing board mounted upon said table, a frame mounted upon said table, a supporting track carried by said frame and extending longitudinally of the pressing board in superposed relation thereto, a pressing iron, a suspension means associated with the track for universal

swinging movement with relation thereto and including a trolley longitudinally rollable on said track, a cable secured at one end to the frame and at its opposite end to the trolley for suspending the trolley in the event of disengagement thereof from the track, and a contractile spring depending from the trolley and connected with the pressing iron for exerting a resilient upward pull on the pressing iron for facilitating the lifting and moving of the same.
